COMBINATION TAPER SQUARE

James I. Hastings, Murfreesboro, Tenn.

Application March 7, 1938, Serial No. 194,466

2 Claims. (Cl. 33—91)

This invention relates to combination taper squares, and more particularly to a combination and adjustable tool which may be used as an ordinary T-square for marking perpendicular lines and laying off rectangular figures or forms and also for laying off tapered figures or forms, as well as locating and marking center lines on both rectangular and tapered drawn figures or forms and actual articles of such shape and also circular figures, forms and articles.

The invention has for its principal object to produce a simple yet practical tool or device of the above noted character which is readily and accurately adjusted and may be dis-assembled and re-assembled, at will, for each particular use.

Another object is to produce a tool which is economically manufactured and may be sold within a reasonable price range for use by the ordinary mechanic, particularly in the wood-working shop, machine shop or sheet metal shop, and other industries.

With these and other objects in view the invention consists in the novel general structure and in the parts and combinations and arrangements of parts as hereinafter more fully described and pointed out with particularity in the appended claims, reference being had to the accompanying drawing illustrating a practical adaptation and application of the invention, in which

Figure 1 is a top plan view showing the device applied to a rectangular figure or object for locating the center line thereof;

Figure 2 is a top plan view showing the device applied to a circular figure or object;

Figure 3 is a fragmentary section taken on or about the line 3—3 of Figure 1;

Figure 4 is a section on the line 4—4 of Figure 1; and

Figure 5 is a plan view showing the device applied to a tapered figure or object.

Referring now to the drawing, the numeral 10 designates a flat base bar or head member, extending perpendicularly from the middle portion of which is a stem blade 11 which is detachably secured at its inner end to the head member 10 by a bolt 12 with a wing nut 13 thereon. To hold the blade 11 against rotation in its perpendicular relation to the head member 10, said head member is preferably provided with a pair of studs 14 which are received in apertures provided therefor in said blade 11 on opposite sides of the pivot bolt 12.

The parts 10 and 11, thus far described, constitute a T-square in their assembled relation, and it may be here noted that when the head mem-

ber 10 is detached from the blade 11 it may be used as an ordinary spirit level, in that it is provided at its middle portion, on one side, with a tubular bubble glass 15 which is supported at its opposite ends on lugs 16 projecting upwardly from the face of the member 10, by which mounting of the bubble glass said member 10 may be placed either edgewise or flatwise when used as a level.

As shown, the head member 10 is provided with aligned longitudinal slots 17 extending from points on opposite sides of the pivot bolt 12 to near the opposite ends of the member and the perpendicular blade 11 is provided with a single longitudinal slot 18 extending substantially the entire length thereof. These slots 17 and 18 are provided for guiding pivot bolts or members of an adjustable frame to be used in connection with the head member 10 and blade 11 in laying off geometric figures and for locating the center lines of such figures or actual objects as will presently be more fully described. This frame, as shown, comprises a pair of bars 19 extending longitudinally on opposite sides of the perpendicular blade 11, said bars 19 being provided at one end with pivot bolts 20 which work in the slots 17 of the head member 10 and are provided with securing nuts 21. A pair of equalizing bars 22 are respectively attached at one end pivotally to the side bars 19 by means of said bolts 20 whereby to be adjusted with the adjacent ends of the bars 19 and locked together therewith on the head member 10 by said nuts 21. The opposite ends of the equalizing bars 22 are pivotally attached to each other by a bolt 23 which works in the longitudinal slot 18 of the blade 11 and is locked in adjusted position by nut 24.

Opposed to the equalizing bars 22 is another pair of similar bars 25 which are pivotally attached, as at 26, to the outer end portions of said side bars 19 and are pivotally connected at their inner ends by a bolt 27 similar to the bolt 23 which connects the other pair of equalizing bars 22, said bolt 27 working in the slot 18 of the blade 11 and being provided with a locking nut 28 similar to the nut 24 on said bolt 23.

By the pivotal connections and mounting of the longitudinal side bars 19 and the equalizing bars or links 22 and 25, said bars 19 may be adjusted at different distances apart and either perpendicularly to the head member 10 and in parallel relation to the blade 11, as shown in Figure 1, or said bars 19 may be inclined and set obliquely with respect to said base member 10 and the blade 11 as shown in Figures 2 and 5. It is

thus obvious that the longitudinal side bars 19 are readily adjusted to coincide with the opposite sides of a geometrical figure or actual object of either rectangular form, as shown in Figure 1, 5 or of tapered polygonal form as shown in Figure 5, and in either case the slot 18 of the stem 11 coincides medially with the figure or object so that a center line may be marked on said figure or object by a pencil or other marking 10 medium inserted in and moved along said slot 18. So, too, a center line may be marked on a circular figure or object, as shown in Figure 2, in which latter case the converged outer ends of 15 said side bars 19 may be brought together in contact with each other, as shown in Figure 2, or they may be spaced apart, as shown in Figure 5, and in either case the converging side bars 19 are brought tangential to the circular or other 20 shape outline of the geometrical figure which is laid out in a drawing or in circumferential contact with a circular or other shape actual article or object.

While the device is particularly adapted for 25 locating and marking center lines on the objects or figures, it is noted that the device may be set to lay out and mark the outlines of rectangular and tapered objects as shown in Figures 1 and 5 by utilizing the side bars 19 as the 30 guide in marking the opposite sides of the figure.

Obviously, the structure admits of considerable 35 modification without departing from the spirit and scope of the invention as defined by the appended claims. The invention, therefore, is not limited to the specific construction shown in the accompanying drawing.

What is claimed is:

1. The herein described adjustable square and 40 taper measuring device, comprising an elongated straight-edged base member having guide means extending lengthwise thereof on opposite sides of its middle portion, a blade member extending 45 perpendicularly from the middle portion of said base member, said base member and blade member constituting a T-square, the blade member having longitudinal guide means extending continuously from end to end thereof, a pair of longitudinal straight-edged side bars located 50 respectively on opposite sides of said blade member and adjustably connected together at their opposite ends by opposed pairs of equalizing bars, the

equalizing bars of each pair being pivotally attached at one end to said side bars and pivotally joined together at their opposite ends and being adjustably secured at the jointure in the longitudinal guide means of said blade member, said longitudinal side bars and the equalizing bars of one pair being adjustably engaged at their respective places of attachment in the guide means of said base member, whereby said side bars may be adjusted and placed in equalized but variably distanced parallel and inclined relation to said blade member, at will.

2. The herein described adjustable square and taper measuring device, comprising an elongated straight-edged base member having aligned longitudinal slots at opposite sides of the middle thereof, a perpendicular blade member rigidly but detachably secured at one end to the middle portion of said base member, said blade member having a longitudinal slot therein extending substantially the entire length thereof, a pair of longitudinal straight-edged side bars disposed respectively on opposite sides of said perpendicular blade member, a pair of equalizing bars pivotally connected at one end, respectively, to the inner 20 ends of said longitudinal side bars, said pair of equalizing bars and pair of side bars being movably mounted at their places of pivotal connection in the longitudinal slots of said base member whereby to be adjusted lengthwise of the base 30 member and transversely with respect to said perpendicular blade member, said pair of equalizing bars being pivotally attached to each other at their opposite ends and movably mounted at the point of their attachment in the longitudinal 35 slot of said perpendicular blade member whereby to be adjusted lengthwise of the member, and an opposed pair of equalizing bars pivotally attached at one end, respectively, to the outer ends of said longitudinal side bars, said opposed pair of equalizing bars being pivotally attached to each other at their opposite ends and movably mounted at the point of such attachment in the longitudinal slot of said perpendicular blade member for adjustment lengthwise of the member, whereby said 45 side bars may be adjusted and placed in equalized but variably distanced parallel and inclined relation to said blade member, at will.
